(57) **CLAIM**

The ornamental design for an external lens for mobile terminal, as shown and described.

DESCRIPTION

FIG. 1 is a perspective view of an external lens for mobile terminal showing our new design;

FIG. 2 is a front view thereof;

FIG. 3 is a rear view thereof;

FIG. 4 is a right side view thereof;

FIG. 5 is a left side view thereof;

FIG. 6 is a bottom view thereof; and,

FIG. 7 is a top view thereof.

The broken lines depict portions of the external lens for mobile terminal in which the design is embodied that form no part of the claimed design.
